CLAIM

I claim the ornamental design for a magnetic bumper sticker with backplate, as shown and described.

DESCRIPTION

FIG. 1 is a front view of a magnetic bumper sticker with backplate.

FIG. 2 is a top view of the magnetic bumper sticker with backplate.

FIG. 3 is a left view of the magnetic bumper sticker with backplate.

FIG. 4 is a bottom view of the magnetic bumper sticker with backplate.

FIG. 5 is a right view of the magnetic bumper sticker with backplate.

FIG. 6 is a back view of the magnetic bumper sticker with backplate; and,

FIG. 7 is an exploded perspective view of the magnetic bumper sticker with backplate.

(Continued)

The broken lines in the drawings illustrate portions of the magnetic bumper sticker with backplate that form no part of the claimed design.
